UNITED STATES PATENT OFFICE.

GODFREY J. BREMER, OF KALAMAZOO, MICHIGAN.

DESIGN FOR A CHECK.

SPECIFICATION forming part of Design No. 30,872, dated May 30, 1899.

Application filed January 5, 1899. Serial No. 701,295. Term of patent 14 years.

To all whom it may concern:

- Be it known that I, GODFREY J. BREMER, a citizen of the United States, residing at Kalamazoo, in the county of Kalamazoo, State of Michigan, have invented and produced a new and original Design for a Check, of which the following is a specification, reference being had to the accompanying drawings, forming a part thereof.
- 5 The check may be put to many uses; but an especial use for which it is intended is to serve as a mercantile check or "chip," as such things are sometimes called, to be given to customers to represent value of goods, &c., as the case may be.
- 10 One object in designing the check in this manner, aside from novelty, is to make it artistically attractive and not easily counterfeited without devoting too much expense to
- 15 make it of advantage to do so.
- In the drawings referred to, Figure 1 is a side elevation; Fig. 2, an edge view looking from a point at either the right or left of Fig. 1, and Fig. 3 is a section on line *c c* in Fig. 1.

The check is made from a solid piece of material, quite thin, so as to have a very narrow appearance, and it has two flat smooth unbroken sides or face-surfaces. It is circular in shape, observed to have every point in its periphery equidistant from its center. In its periphery is formed a deep narrow channel 4 4, the sides of which are perpendicularly straight to the base of said channel. The base of the channel horizontally, across it at all points, is straight and at a strict right angle to the perpendicular sides, and said base is circular with the same degree of accuracy as the circular periphery.

Having thus described my invention, what I claim as new, and desire to secure by Letters 40 Patent of the United States, is—

The design for a check, substantially as herein shown and described.

GODFREY J. BREMER.
